UNITED STATES PATENT OFFICE.

THEODORE J. RADKE, OF OAK PARK, ILLINOIS.

VALVE-CONTROLLING MECHANISM FOR WATER HEATERS.

Application filed September 28, 1925. Serial No. 58,989.

The present invention relates to mechanisms for controlling a valve, such as a fuel valve, so that it will always be fully open or fully closed, except for an instant while it is shifting from one position to another, the opening and closing being effected by mechanism under the control of a variable temperature or the like; whereby the valve is quickly opened when a predetermined low temperature is reached and is again quickly closed when the temperature rises to a predetermined value. The object of the present invention is to produce a valve-controlling mechanism of this type that shall be simple in construction, consist of a few simple durable rugged parts, and be efficient and reliable in operation.

Specifically stated, my invention comprises a valve tending constantly to close, a lever mechanism for opening the valve, a lock for holding the valve open, and a simple snap action tripping device under the control of a thermostat or other prime mover for actuating the lever mechanism to quickly open the valve and then, when the proper conditions are reached, to place the actuating lever mechanism in an inoperative position and finally unlock the valve so as to permit it to close. The valve is therefore either fully open or fully closed so that the fuel is either turned on fully or is completely shut off, avoiding waste of fuel on account of incomplete combustion which would result if the valve were opened or closed slowly, and preventing the formation of soot in the heater whose supply of fuel is being controlled.

The various features of novelty whereby my invention is characterized will herein-after be pointed out with particularity in the claims; but, for a full understanding of my invention and of its objects and advantages, reference may be had to the following detailed description taken in connection with the accompanying drawings, wherein:

Figure 1 is an elevation of a controlling mechanism arranged in accordance with the present invention, the valve being shown in section, and there being shown also a portion of a thermostatic controller; Fig. 2 is a view similar to Fig. 1, showing the parts in the positions which they occupy when the valve is open, whereas in Fig. 1 the parts are in the positions which they occupy when the valve is closed; Fig. 3 is a section taken approximately on line 3—3 of Fig. 2, the

device being inverted from the position shown in Fig. 2; Figs. 4 and 5 are edge views of the two members of the compound actuating lever for opening the valve and Fig. 6 is a section through the locking device or trigger taken approximately on line 6—6 of Fig. 2.

Referring to the drawings, 1 represents a casing adapted to be supplied with a cover, not shown. Attached to the lower end of the casing is a valve body 2. The passage through the member 2 is controlled by an upwardly seating valve 3 mounted on a vertical stem 4 with slides in lower and upper guides 5 and 6. A spring 7, surrounding the valve stem below the valve, tends constantly to close the latter by moving it upwardly. Extending upwardly through the valve body is a plunger 8 axially aligned with and resting on the valve stem. This plunger passes through a suitable bearing 9 in the bottom wall of the casing 1 into the casing. Just below the upper end of the plunger there is an annular groove 10 that lies just above the bottom wall of the casing when the valve is open. The valve is adapted to be locked in its open position by a lip 11 fixed to the end of a swinging locking trigger 12; the trigger being pivoted to the casing at a point 13 such that when the free end is swung toward the plunger the lip 11 will enter the groove when the valve is open and thus hold the valve open. A spring 14 acts on the trigger in a direction tending constantly to hold it in its locking position, as shown in Fig. 1. When the trigger is withdrawn from locking engagement with the plunger, and the plunger is otherwise unrestrained, the valve is closed by its spring 95 as shown in Fig. 2, the plunger projecting upwardly into the casing at this time.

The closing of the valve is effected by a compound lever consisting of two members 15 and 16. The member 15 is pivoted between its ends to the rear wall of the casing, as indicated at 17; one arm projecting past the end of the plunger and having a lip 18 adapted to bear against said end under certain conditions. The lever 16 is hinged at one end, as indicated at 19, to the rear wall of the casing, and extends in front of the lever 15 past the vertical axis of the plunger. A strong spring 20 is connected between the lever 16 and a portion of the casing, this spring tending constantly to swing the free end of this lever upwardly. The lever 16

is provided with a fixed pin or projection 21 extending rearwardly therefrom underneath the right hand end of the lever 15; the pin or projection being only a short 5 distance from the pivotal axis of the lever 16. Therefore, when the spring 20 is left free to do so, it swings the lever 16 upwardly and, through the engagement of the pin 21 with the lever 15, swings the latter in a 10 counter-clockwise direction as viewed in Fig. 2; thus forcing the left hand end of the lever 15 down and causing the lip 18 on this lever to press down on the upper end of the plunger. The spring 20 is strong 15 enough to overcome the resistance of the spring in the valve and therefore, when the spring 20 is left free to act, it causes the valve to be pressed down from the closed position shown in Fig. 2, to the open position 20 shown in Fig. 1.

The compound lever and the locking trigger are controlled by a tripping cam 22 pivoted, as indicated at 23, to the rear wall of the casing at one end thereof. The edge 25 of this cam cooperates with a projection 24 on the locking trigger to force the trigger into an idle position and again to permit it to assume its locking position. The projection 24 may conveniently be a screw 30 passing through the trigger, thereby permitting adjustments to be made in order properly to time the movements of the trigger. The tripping cam has such a contour that when it is at one limit of its swinging 35 movement, it is clear of the screw on the trigger and thus permits the trigger to be fully entered into the notch in the valve-actuating plunger when a valve is open. On the other hand, as the cam approaches 40 the other limit of its movement, as shown in Fig. 2, it forces the trigger into its idle position. On the free end of the cam is a projecting pin 25 that overlies the free end of the lever 16. This end of the lever is 45 peculiarly shaped, taking the form of an upwardly inclined finger having at the lower inner end thereof and again near the outer end, on the upper side, a concave seat, as indicated at 26 and 27, respectively, 50 for the reception of the pin 25.

The parts are so proportioned that, assuming them to be in the positions shown in Fig. 2, and that the cam 22 begins to swing in a counter-clockwise direction: the pin 25 55 will ride out of the seat 27, slightly depressing the lever 16, and the trigger will be permitted to swing toward the right until it rests against the side of the valve-actuating plunger. After the pin has 60 moved completely clear of the seat 27 and is riding on the straight inclined upper edge of the outer end of the lever 16, this inclined edge acts as a cam or wedge which, under the influence of the spring 20, pushes 65 the pin 25 quickly toward the right and

completes the swinging motion of the cam into the position shown in Fig. 1. While the lever 16 is acting to complete the swinging motion of the cam, it is rising, and the pin 21 thereon is forcing the right hand end 70 of the lever 15 up, and the left hand end down, thereby forcing the plunger 8 down and opening the valve. The spring 20 is sufficiently powerful to cause the levers to move with a snap action as soon as the pin 75 25 has reached the position where the levers are left free to act. Consequently the valve is opened with a snap action. The valve also closes with a snap action as will herein-after be explained. 80

The device that I have illustrated is intended to control the flow of gas to a burner adapted to heat water in a tank, whereby when the temperature of the water drops to a predetermined low level, the gas will 85 be turned on and, when the temperature rises to a predetermined maximum level the gas will be again turned off. The mechanism that I have heretofore described is therefore shown as controlled by a thermostatic device, the casing 30 of which extends through the wall of a tank containing water to be heated, the casing having a screw-threaded portion 31 at the point where it enters the tank for the purpose of forming 90 a tight closure of the opening and at the same time supporting the thermostatic device from the tank. The outer end of the casing for the thermostat extends through one of the side walls of the casing 1 and 95 is screwed to the latter casing by any suitable means as, for example, screws 32 passing through flanges 33 on the member 30 and into the rear wall of the casing 1. The movable element of the thermostat is 100 a part 34 that projects slightly beyond the outer end of the thermostat casing. The part 34 is adapted to act on a swinging controlling arm 35 pivoted at its upper end to the rear wall of the casing 1 near the top 105 thereof and hanging down opposite the end of the thermostat. On the lower end of the arm 35 is a finger 36 that extends into the space between two separated horns 37 and 38 on the tripping cam 22. Between the 110 arm 35 and the casing is a spring 39 tending constantly to hold the arm against the thermostat. If desired, the thermostat element 34 may cooperate with the head 40 of the screw 41 extending into or through the 115 arm 35; this screw being adjustable. In the arrangement shown, there is a locking nut 42 on that end of the screw that projects through the arm. 120

When the temperature in the tank drops, the element 34 of the thermostat moves toward the left whereas, upon a rise in temperature, it moves toward the right. During the first of these movements, the spring 39 causes the swinging arm 35 to follow 125 130

after the receding thermostat element while, during the second of said movements, the arm 35 is swung in the counter-clockwise direction against the resistance of its spring. 5 In Fig. 1 the parts are shown in the positions which they occupy when the temperature of the water has dropped to the predetermined minimum. The valve is now open and the finger 36 on the controlling arm is held out of engagement with both of the 10 horns on the cam. The valve being open, fuel is supplied to the burner, so that the water is heated. As the temperature of the water rises, the element 34 of the thermostat will gradually move toward the right, pushing the controlling arm ahead of it. After this movement has continued for some time, the finger 36 on the controlling arm will engage with the horn 38, causing the 15 tripping cam to swing in a clockwise direction. The pin 25 begins to ride up the inclined end of the lever 16, pressing this lever down against the resistance of its spring and leaving the lever 15 free of any restraining influence, since the pin 21 drops away from this lever. Just as the pin 25 is ready to drop into the seat 27, the cam forces the locking trigger 12 toward the left, releasing it from the valve actuating plunger. There 20 is now nothing to prevent the spring in the valve from forcing the valve and plunger up, and therefore the valve will be instantly closed, the plunger rocking the lever 15 in the clockwise direction until its right hand 25 end is almost in contact with the pin 21; the parts being now in the positions indicated in Fig. 2 and the lever 15 being still out of contact with the pin 21 so as to insure that it will not interfere with the complete seating of the valve. The final swinging movement of the tripping cam is brought about 30 by the lever 16 and not by the controlling arm. It will be seen that the valve remains locked in its open position until at the instant when the compound lever reaches a 35 position that will permit the plunger to rise to the upper limit of its movement, so that the valve closes with a snap action. As heretofore explained, the valve opens with a 40 snap action, and therefore it may be said to be always fully open or fully closed.

The finger on the controlling arm does not touch either of the horns on the cam when the arm and the cam are at either limit 55 of their movements. Therefore, when the temperature is rising from the predetermined minimum, the controlling arm will swing through an appreciable angle before it begins to actuate the cam. The same is 60 true when the temperature begins to drop from the upper limit. The purpose of this is to permit the controlling arm to swing without doing any work during a portion 65 of the temperature range, as it is only required that the cam be moved near the end

of each swinging movement of the controlling arm. The parts are therefore so designed that the controlling arm serves only to swing the cam through a small angle, in order to bring the line between the axes 70 of the pin 25 and the pivot 23 slightly past center, in order to permit the force of the spring 20 to become effective in order to complete the swinging of the cam in either direction. 75

While I have illustrated and described with particularity only a single preferred form of my invention, I do not desire to be limited to the exact structural details thus illustrated and described; but intend to cover 80 all forms and arrangements which come within the definitions of my invention constituting the appended claims. 85

I claim:

1. The combination with a valve, of a 90 spring tending constantly to close the same, a lever means tending constantly to open the valve, a trigger for locking the valve open, and a movable device constructed and arranged to hold the trigger in its release position and the lever means in an idle position in one position of the device and permit the trigger to assume a locking position and the lever means to open said valve in another position of said device. 95

2. The combination with a valve, of a 100 lever means tending constantly to open the valve, a trigger for locking the valve open, and a movable device constructed and arranged to hold the trigger in its release position and the lever means in an idle position in one position of the device and permit the trigger to assume a locking position and the lever means to open the valve in another position of said device. 105

3. The combination with a valve, of a 110 lever mechanism tending constantly to open the same, a trigger for locking the valve open, and a movable cam device cooperating with the said trigger and said mechanism to move said lever mechanism out of operative relation to the valve while the latter is open and subsequently release the trigger. 115

4. The combination with a valve, of a 120 lever adapted to engage with a part on the valve to open the same, a second lever having a part adapted to engage with the first lever and cause the latter to open the valve when the second lever is swung in one direction, a spring tending constantly to swing the second lever in said direction, a trigger for locking the valve in its open position; and a controlling device for swinging the second lever in the direction opposite to the aforesaid direction, when the valve is locked open, 125 and then releasing the trigger to permit the valve to close. 130

5. The combination with a valve, of means tending constantly to close the same, a trigger for locking the valve open, a lever mech-

- 4
- anism tending constantly to operate in a direction to open the valve, a swinging member having two positions in one of which it restrains the lever mechanism and in the second of which it permits said mechanism to open the valve, said member having a part engaging with said trigger in the first of said positions to release the trigger, means for swinging said member a portion of the 10 distance from each of its positions toward the other, and cooperating elements on said lever mechanism and said member for causing the completion of the movement of the said member in each direction to be effected by the action of said lever mechanism.
6. The combination with a valve, of means tending constantly to close the same, a lever mechanism tending constantly to open the valve, a trigger for locking the valve open, 20 and a movable cam device cooperating with said trigger and said mechanism to move said lever mechanism out of operative relation to the valve while the latter is open and subsequently release the trigger.
25. 7. The combination with a valve, of a trigger for locking the valve open, a lever mechanism tending constantly to operate in a direction to open the valve, a swinging member having two positions in one of 30 which it restrains the lever mechanism and in the second of which it permits said mechanism to open the valve said member having a part engaging with said trigger in the first of said positions to release the trigger, 35 means for swinging said member a portion of the distance from each of its positions toward the other, and cooperating elements on said lever mechanism and said member for causing the completion of the movement 40 of said member in each direction to be effected by the action of said lever mechanism.
8. In a mechanism of the character described, a swinging lever, a spring tending to swing the lever in one direction, an 45 oscillating member having a part adapted to ride along a section of the lever and limit the movement produced by the spring means for moving said member from each end of said section toward the other end, 50 said section of the lever being so disposed with respect to the axis of oscillation of said member that it acts as a cam acted on by said spring to complete the movement of said member after it has been moved to a 55 predetermined point by said means.
9. In combination, a valve, lever mechanism for opening the valve, a spring acting on said lever mechanism in a direction to cause said mechanism constantly to tend 60 to open the valve, a trigger for locking the valve open, a swinging member having a part adapted to ride on a section of said lever mechanism from one limit of its movement 65 to the other, means for moving said member from each limit a fraction of the distance 70 to the other limit, said lever section being so disposed that it acts as a cam actuated by said spring to complete the swinging movement of said member in each direction, the parts being so arranged that when said member is at one limit of its movement the lever mechanism is left free to open the valve and when it is at the other limit said mechanism is restrained from opening the valve, and a part on said swinging member for engaging 75 with the trigger and tripping it as said member nears the last-mentioned limit.
10. The combination with a valve of a swinging controlling arm, means to actuate said arm in each direction, a swinging member having separated shoulders between which said arm extends and by which said arm moves said member after the lost motion has been taken up, lever mechanism for operating the valve, a spring acting on said 80 lever mechanism in a direction tending to cause it to operate the valve, cooperating parts on said lever mechanism and said swinging member adapted to restrain said lever mechanism from operating said valve 85 when said member is at one limit of its movement and permit it to operate the valve when said member is at the other limit of its movement, said parts being also so constructed that said lever mechanism completes the swinging movement of said member in each direction after the controlling arm has carried it to a predetermined point. 90
11. The combination with a valve having a spring tending constantly to open it, a swinging member having shoulders spaced apart, a movable controlling device considerably narrower than the space between said shoulders playing between them for swinging said member, lever mechanism for opening the valve, a spring tending constantly to actuate said lever mechanism in a direction to open the valve, cooperating parts on said lever mechanism and said member for completing the throw of the latter through the 100 action of said spring when said member is moved a limited distance in either direction by said controlling device, said cooperating parts being also so constructed that in one of its extreme positions said member restrains the lever mechanism against opening said valve and in its other extreme position permits it to act to open the valve, a trigger for locking the valve open, and a part on said member for tripping the trigger when said member reaches the first-mentioned extreme position. 105
- 120
- In testimony whereof, I sign this specification.

THEODORE J. RADKE.
